DUST PAN

Fred Stark, 9043 Clifton Ave., Niles, Ill.

Filed Sept. 10, 1964, Ser. No. 81,673

Term of patent 14 years

(Cl. D44—18)

FIGURES 2 and 3 are side and rear elevational views, respectively, thereof;

I claim:

The ornamental design for a dust pan substantially as shown.
